JULES A. NY, OF BERKELEY, CALIFORNIA.

PROCESS AND APPARATUS FOR COVERING LITHOGRAPH ROLLS.

1,407,163.

Specification of Letters Patent. Patented Feb. 21, 1922.

Application filed April 7, 1920. Serial No. 372,056.

To all whom it may concern:

Be it known that I, JULES A. NY, a citizen of the United States, residing at Berkeley, in the county of Alameda and State of California, have invented a new and useful Improvement in Processes and Apparatus for Covering Lithograph Rolls, of which the following is a specification.

This invention relates to a process of and 10 an apparatus for covering lithograph rolls.

It is the principal object of the present invention to provide an apparatus by which skins may be drawn over and pulled off of lithograph rolls in a continuous operation 15 at a uniform pressure, thus insuring that the roll will be smoothly and rapidly covered.

The present invention contemplates the use of a fixed mandril onto which a lithograph roll is positioned, said mandril being 20 equipped with power means for engaging a collar detachably secured to the skin of a lithograph roll and by which means the roll may be pulled onto the lithograph roll or removed therefrom.

25 The invention is illustrated by way of example in the accompanying drawings, in which:

Figure 1 is a view in side elevation illustrating the principal parts of the present invention broken away for the sake of convenience.

Fig. 2 is a view in side elevation showing the opposite side of the apparatus.

Fig. 3 is an enlarged fragmentary view 30 disclosing the gripping action of the collar.

Referring more particularly to the drawings, 10 indicates a bed plate. This plate may be supported upon a suitable sub frame and is formed with opposite end standards 40 11 and 12. These standards are bored to receive a guideshaft 13 which extends parallel to the bed plate 10 and carries a supporting member 14. The supporting member 14 is formed with a semi-circular depression to 45 conform to the cylindrical surface of a lithograph roll 15. This roll is adapted to be removably disposed upon a mandril 16, which mandril extends horizontally and parallel to the shaft 13 and is rigidly secured in the face 50 of a pressure block 17. This block is formed integral with the standard 12 and extends vertically therefrom. Bearing plates 18 are formed integral with the standard 12 and provide bearings 19, 20 and 21 have shafts 55 22, 23 and 24. The shaft 22 is uppermost and extends transversely of the longitudinal

axis of the machine. This shaft carries a pair of sprocket wheels 25 and a gear 26. The sprocket wheels are spaced a considerable distance from each other to receive 60 sprocket chains 27 which extend forwardly along opposite sides of the pressure block 17 and detachably engage a collar 28 by means of hooks 29. The hooks 29 will receive pins 30 extending radially from the opposite sides of the collar. The gear 26 is in mesh with a pinion 30. This pinion is secured upon the end of shaft 23 and may rotate with this shaft as actuated by the operating crank 31. The shaft 24 is provided to receive idler 70 rollers 32 over which the sprocket chains 27 may extend and by which rollers the sprocket chains are maintained in constant mesh with the sprockets 25.

The collar structure 28 is more clearly 75 shown in Fig. 3 and comprises an inner sleeve 33 and an outer sleeve 34 telescoping thereover. The adjacent faces of these sleeves are tapered so that the sleeve 33 may slip within the sleeve 34 and become wedged 80 into position. A plurality of circumferentially extending corrugations 35 are formed around the tapered portion of the sleeve 33 and are adapted to become embedded within a wall of the roller skin 36 to grip this skin. 85 A combined clamping and ironing roller 37 is provided and may be used to either iron out the wrinkles in the skin or hold it in its stretched position while the end of the skin is sewed around the end of the roller. 90

In carrying out the present invention a lithograph roll which has a mandrel 16 formed integral therewith or otherwise permanently secured thereto is set up in the machine with one end of the mandrel engaging 95 the pressure block 17, the opposite end of the roll being supported by the member 14. If it is desired to remove the old skin, the collar structure 28 is clamped thereto, pulling action is then transmitted to the collar structure 28 by the chains 27, as the collar is moved along the roll lengthwise it pulls the skin with it, thus removing the same from the roll. In the event that the lithograph skin is to be placed over a roll the roll is 100 mounted upon the machine as indicated in Figs. 1 and 2 and the collar structure 28 is considered to grip one end of the skin as shown in Fig. 3. Pins 29 of the sleeve member 34 may then be engaged by the hooks 110 of the sprocket chains 27 after which these chains may be drawn by operation of the

gears 26 and 30 through movement of the crank 31. This action will gradually and continuously pull the skin over the roll and to a seated position as shown in Fig. 2. 5 When the skin has been tightly drawn into place a two part clamping collar 37 may be secured around the roll to clamp the skin at a point near the forward or at the opened end thereof. It is then desirable to remove 10 the hooks from the pins upon sleeve 34 and place them upon pins 39 of the inner sleeve 33. By further drawing upon this sleeve the collar member may be removed from its engaging position relative to the skin at the 15 same time the clamping collar will hold the skin and permit the ends thereof to be sewed around the ends of the mandril. In the event that there are any irregularities or wrinkles in the skin as it has been pressed 20 over the lithograph roll, it may be ironed out by the use of the clamping collar 37 which may be tightly secured over the roll and around the skin and drawn longitudinally thereof by the chains 27, the hooks of 25 which engage suitable pins carried by the collar. It will be understood that during the operations described the roll will be supported by the member 14 at its outer end.

It will thus be seen that by the present 30 simple and inexpensive machine, lithograph rollers may be rapidly covered or uncovered and when covered the skin will be tightly stretched and smoothly drawn over the surface of the roller by continuous and direct 35 operation.

While I have shown the preferred form of my invention as now known to me, it will be understood that various changes in the construction, combination and arrangement of 40 parts may be made by those skilled in the art without departing from the spirit of the invention as claimed.

Having thus described my invention, what I claim and desire to secure by Letters 45 Patent, is:

1. A method of covering lithograph rolls which consists of gripping one end of the lithograph roll skin and drawing it over the roll in a continuous operation, thereafter 50 clamping the skin to prevent shrinkage during which time the clamping means may be removed and then sewing the skin around the end of the mandril to maintain it in its stretched condition.

2. A machine of the class described comprising a supporting mandril for lithograph rolls, means for engaging a lithograph skin and means for exerting a continuous pull upon said means to draw the skin over the 55 roll.

3. A machine of the class described comprising a supporting mandril for lithograph rolls, means for engaging a lithograph skin and means for exerting a continuous pull upon said means to draw the skin over the 60 roll, and means for ironing the skin when it is in position upon the roll.

4. A device of the character described comprising a base, a horizontally extending mandril secured by one end to the base and 70 adapted to receive a lithograph roll, a clamping collar for engaging a lithograph roll cover and power means acting to pull upon said cover clamp to draw the cover onto the roll.

5. A device of the character described, comprising a base, a horizontally extending mandril secured by one end to the base and adapted to receive a lithograph roll, a clamping collar for engaging a lithograph roll 80 cover and power means acting to pull upon said cover clamp to draw the cover onto the roll, and means for releasing said clamp from the cover.

6. A device of the character described, comprising a base, a horizontally extending mandril secured by one end to the base and adapted to receive a lithograph roll, a clamping collar for engaging a lithograph roll cover and power means acting to pull 90 upon said cover clamp to draw the cover onto the roll, and means for releasing said clamp from the cover, and means for holding the cover in its stretched position over the roll while the clamp is released and the cover 95 secured in position.

7. A device of the character described comprising a main frame, a horizontally extending mandril secured by one end to the main frame and adapted to receive a lithograph 100 roll, a supporting member adjustably disposed relative to the mandril for the support of the lithograph roll at the free end of the mandril.
